(57) **CLAIM**

The ornamental design for wireless charger for electric vehicle, as shown and described.

DESCRIPTION

FIG. 1 is a perspective view of a wireless charger for electric vehicle according to the present invention.

FIG. 2 is a front view of a wireless charger for electric vehicle of FIG. 1.

FIG. 3 is a rear view of a wireless charger for electric vehicle of FIG. 1.

FIG. 4 is a left side view of a wireless charger for electric vehicle of FIG. 1.

FIG. 5 is a right side view of a wireless charger for electric vehicle of FIG. 1.

FIG. 6 is a top view of a wireless charger for electric vehicle of FIG. 1; and,

FIG. 7 is a bottom view of a wireless charger for electric vehicle of FIG. 1.

The broken lines in the drawings illustrate portions of the wireless charger for electric vehicle that forms no part of the claimed design.
